UNITED STATES PATENT OFFICE.

JOHN WALTER WILSON, OF INDIANAPOLIS, INDIANA.

COMB.

1,382,586.

Specification of Letters Patent. Patented June 21, 1921.

Application filed January 18, 1921. Serial No. 438,213.

To all whom it may concern:

Be it known that I, JOHN WALTER WILSON, a citizen of the United States, residing at Indianapolis, in the county of Marion and State of Indiana, have invented new and useful Improvements in Combs, of which the following is a specification.

My present invention has reference to a comb which is particularly designed for applying a desired quantity of dye to hair for restoring the color thereof.

The primary object of the invention is to produce a comb for this purpose in which the dye can be applied in desired or determined quantities without being rubbed in the scalp or inflicting injury thereto, and without danger of staining the hands of the operator.

The foregoing and other objects which will appear as the nature of the invention is better understood, may be accomplished by a construction, combination and operative arrangement of parts such as is disclosed by the drawings which accompany and which form a part of this application.

In the drawings:

Figure 1 is a perspective view of a comb constructed in accordance with the present invention.

Fig. 2 is a substantially central vertical longitudinal sectional view therethrough.

Fig. 3 is a sectional view on the line 3—3 of Fig. 2.

Fig. 4 is a view of the comb element detached, parts being broken away.

Fig. 5 is a similar view of the handle member, with the cap disconnected therefrom.

Fig. 6 is a similar view of the dye containing sack.

Referring now to the drawings in detail, the improvement is broadly indicated by the numeral 1, and comprises essentially a comb proper which is indicated by the numeral 2 and a handle which is indicated by the numeral 3. The comb is of substantially rectangular formation, having the body portion, or the portion thereof above the teeth, comparatively wide. For distinction this body portion is indicated by the numeral 4.

Against one face of the body there is arranged a fabric sheet 5, which is held on the body and compressed thereagainst by a plate 6, which is removably secured to the body by means 7. The plate 6 on its outer face is centrally provided with a boss 8 that has a

threaded bore designed to be engaged by a threaded extension 9 on the tubular handle 3. The extension 9 is in the nature of a piping, and passing therethrough is the restricted neck portion 10 of the compressible sack 11 which contains the dye. The sack is of a length slightly less than that of the bore of the handle, and has bent against its outer and closed end a reinforcing metallic element 12. Arranged against one face of the sack 11 there is a metallic plate 13 which, of course, is received in the bore of the handle. The neck portion 10 of the sack projects a suitable distance beyond the threaded or pipe-like member on the end of the handle, and this projecting portion provides a washer or gasket which contacts with the fabric sheet 5 as well as with the bore of the boss 8, so that the fluid from the sack will not pass through the handle and plate 6, at the connected portions thereof.

The outer and open end of the handle is normally closed by a threaded cap 15, and on one side of the handle there is an outstanding bifurcated boss 16 between the arms of which there is pivotally connected a link 17, that is in turn pivotally connected to one end of a lever 18. The lever 18 has pivotally secured thereto a pin or rod 19 that passes through a suitable opening 20 in the handle and is in contacting engagement with the compressor plate 13. The tension exerted by the spring normally holds the lever 18 at an angle with respect to the handle. The outer end of the lever is flattened, and a pressure thereof will cause the pin or rod to be moved inwardly of the handle and force the compressor plate against the sack, thus ejecting fluid from the said sack, and directing the same against the fabric sheet 5. By reference to the drawings it will be noted that the construction of the body 4 of the comb, and the plate 6, is such that only the edges and outer end of the fabric 5 are tightly compressed therebetween and also that the fabric projects onto the toothed portion of the comb. Thus by operating the lever the dyeing fluid will saturate the projecting end of the fabric, and by drawing the comb through the hair a proper amount of dye can be applied thereon.

The improvement may be constructed of any desired materials. The normally angularly arranged handle is directed toward the comb end of the device and is at a proper

angle to receive thereon the thumb of the operator. It will be further apparent that by removing the handle from the comb proper, and inserting the same into a receptacle containing a dye, the lever may be reciprocated to permit of the compression and expansion of the sack, and thus cause the fluid to be drawn into the sack through the neck thereof.

10 It is believed that the foregoing description, when taken in connection with the drawings, will amply set forth the construction and operation to those skilled in the art to which such inventions relate.

15 Having thus described the invention, what is claimed as new, is:—

1. A dying comb including a comb proper, a fabric or sheet on the body portion thereof, a hollow handle arranged right angularly with respect to the comb, means for removably securing the handle to the comb, a dye sack in the handle having a mouth portion communicating with the fabric, and means on the handle for compressing the 25 sack to eject fluid therefrom onto the fabric.

2. In a hair dying comb, a comb proper having a fabric sheet on the body portion thereof, the end of which being arranged over the teeth, a plate secured to the comb 30 and compressing the edges and ends of the fabric against the body of said comb, a handle removably secured to the plate, a dye containing sack in the hollow handle having a reduced neck portion passing therethrough 35 and disposed in contacting engagement with the fabric sheet, and means on the handle for compressing the sack to eject fluid therefrom onto the fabric.

3. A hair dying comb including a comb proper having a flat portion providing a body beyond the teeth thereof, a sheet of absorbent material resting on the body and

having an end projecting onto the toothed portion of the comb, a plate arranged over the sheet, secured to the body of the comb, 45 and compressing the outer edge and the ends of the sheet against said body, a removable hollow handle threadedly connected with the plate, a dye containing sack in the handle having a reduced neck portion entering the 50 plate and contacting with the sheet, a flat plate in the bore of the handle in contacting engagement with the sack, a lever pivotally supported on the handle, a pin therefor passing through an opening in the 55 handle and secured to the flat plate and the handle portion of the said lever being directed toward the comb.

4. In a hair dying comb, a comb proper having a body portion, an absorbent sheet 60 thereon, having an edge projecting onto the toothed surface thereof, a plate secured to the body and compressing the outer end and edges of the sheet against the body, said plate having an outstanding boss provided 65 with a threaded bore, a hollow handle having an outer open end, a cap for closing the same, and a reduced threaded extension at the inner end thereof, which latter is designed to be received in the bore of the 70 plate, a dye containing sack in the handle having a neck portion projecting through the threaded extension of the handle and arranged laterally against the end thereof to provide a gasket, a compressor element in 75 the bore of the handle contacting with the sack, a pivoted operating lever on the handle, a pin carried thereby entering the handle and engaging the compressor element and retaining the lever normally at an angle 80 with respect to the handle.

In testimony whereof I affix my signature.

J. WALTER WILSON.
